Primary Examiner — Kevin K Rudzinski*Assistant Examiner* — Xavier Marti-Santos(74) Attorney, Agent, or Firm — Birchwood IP(57) CLAIM

The ornamental design for a hair curler head, as shown and described.

DESCRIPTION

FIG. 1 is a perspective view of a hair curler head, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a partial enlargement drawing of FIG. 1.

The broken lines depict portions of the hair curler head that form no part of the claimed design. The dash-dot broken lines in the figures are demarcating enlarged areas and form no part of the claimed design.
